JESSE A. B. SMITH, OF BROOKLYN, NEW YORK, ASSIGNOR TO UNDERWOOD TYPEWRITER COMPANY, OF NEW YORK, N. Y., A CORPORATION OF DELAWARE.

TYPE-WRITING MACHINE.

1,237,716.

Specification of Letters Patent. Patented Aug. 21, 1917.

Application filed July 12, 1915. Serial No. 39,247.

To all whom it may concern:

Be it known that I, JESSE A. B. SMITH, a citizen of the United States, residing in Brooklyn borough, in the county of Kings, city and State of New York, have invented certain new and useful Improvements in Type-Writing Machines, of which the following is a specification.

This invention relates principally to type-writing machines for writing upon a number of superposed webs or continuous sheets, especially those which are intended to be torn off in sections from the body of the web, as, for example, when the webs comprise a series of printed forms, each adapted to be removed when the typewriting thereon is completed. In such work it is desirable to employ ink ribbons or carbon sheets interleaved with the webs for making the duplicate copies. A machine of this general character is shown and described in the patent to Werner and Smith No. 1,132,055, dated March 16, 1915. In that machine, after a section of web, to compose a printed sheet, has been written, the platen is shifted away from the usual feed rollers to release the web and the interleaved carbon sheets; whereupon, by means of a carbon sheet holder, the carbon sheets are drawn back along the web into position thereon for the printing of the next web section; the web itself being drawn forward a measured distance for removal of the printed section thereof, and the next imprinted section thereof being positioned, with the carbon sheets therein, for the printing operation. The same carbon sheets are thus used over and over in the same web form.

Heretofore, in interchanging web forms in the machine, it has been necessary at the time of such change, separately to detach the carbon sheets from their holder in removing the web from the machine, and separately to re-attach the carbon sheets to the holder in their interleaved position in the new web. These operations have involved delay and inconvenience which had often made it desirable to use two or more machines rather than to change webs frequently in one machine. It is an object of the present invention to provide interchangeable holders for the carbon sheets and webs; so that, without disturbing either the web or the carbon sheets on the holder, they may be removed as

a unit from the machine; and so that another web form with carbon sheets already interleaved therewith and mounted on another holder of the same style, may be substituted without delay for that removed. In the preferred form of the invention, the sheet holders may be plates with clips for securing the carbon sheets thereto, and with pins or other means for centering the plates on the carriage by means of which the sheet holder is fed toward and from the platen. The carriage may carry guide-pieces to assist the operator in centering the sheet holders thereon. Ordinarily the holders may be removed by simply lifting the same from the carriage.

A further object of the invention is to provide, in a machine of the character described, reliable means for guiding the leading edge of the web around the platen, past and beyond the printing line. It is common in these machines to have a knife blade, located above the printing line, for cutting off the printed sections of the web. Quite commonly, typewriting machines are provided with gage plates secured at the front of the machine which have base lines, with scale marks thereon at letter-feed distances apart, to assist the operator in alining and positioning a line of print for writing therein. Neither such cutters nor such gages have heretofore been used as paper guides in such a way as to assure absolutely certain guidance of the leading edge of the paper at or near the printing point. Such use of these parts is a feature of the present invention. To this end, the gage plates referred to are extended up in the form of spring clips to bear against the platen near the printing point, and to extend above the printing line. The scale lines of the gages at the printing line are formed by the base lines of the aperture cut through the gages at an intermediate part thereof. In order that the cutter may be used to guide the paper beyond the point where the gages cease to do so, the cutter is mounted to be moved downward, from its normal cutting position, to a point where it co-operates with the gages to form with the latter a substantially continuous guiding surface for the leading edge of the web at the front of the platen. For this purpose, the cutter may be

mounted on arms adapted to be rocked on the platen shaft, and a key lever may be provided for holding the cutter in normal position, and for effecting movement of the same when desired.

A further feature of the invention relates to a means for assuring proper alinement of the leading edge of the web after it has been released, and when it is drawn forward 10 to the gage, preparatory to the cutting operation. Without some such means the advanced section of the web, which at this time is loose in the machine, may be accidentally tipped to one side or other and 15 held against the gage at an angle; so that, when cut, it will not be cut squarely. The preferred device of the present invention, for maintaining and assuring proper position of web for cutting, is a blade on the 20 shelf over which the web is drawn to the gage; this blade serving as a guide for one edge of the web as the latter is drawn to the gage, and also serving, in conjunction with the gage, as a means for squaring up the advanced section of the web when the latter is 25 at the gage. The gage is preferably adjustable lengthwise of the platen for webs of different widths.

A further feature of the invention relates 30 to the provision of means for protecting the web against being torn by the free ends of the carbon-sheet-holding fingers, as the carbon-sheet-holder is returned or moved to a new position relative to the web, such means 35 also serving to straighten or smooth the webs as the said holder is returned. Such means may consist of guards or shields, each in the form of a flat sheet-metal plate removably attached to the free end of a carbon-sheet-holding finger, said guard plate 40 extending rearwardly from the finger and having its outer edge inclined inwardly from the end of the finger; so that the guard will engage the web some distance inwardly 45 from the folds of the web and in advance of the said finger to straighten the web and prevent it from being torn at its fold.

Other features and advantages will hereinafter appear.

50 In the accompanying drawings,

Figure 1 is a perspective view of the invention applied to an Underwood typewriting machine, the parts being in position to permit writing upon a work-piece.

55 Fig. 2 is a detail perspective view of the platen with the combined paper guide and cutter mounted on the platen shaft in operative relation to the platen.

Fig. 3 is a fragmentary view, illustrating 60 a guard plate or shield, attached to one of the sheet-holding fingers, and illustrating its operation in protecting and straightening the web as the carbon sheets are moved rearwardly relatively to the web.

65 Fig. 4 is a sectional view, taken on the line

3—3 of Fig. 1, of certain of the parts, assembled on the carriage, in normal or printing position.

Fig. 5 is a view similar to that of Fig. 4, except that the combined guide and cutter is shown in the position in which it acts to guide or direct the leading edge of the web around the platen to position, preliminary to printing.

Fig. 6 is a perspective view of one of the 75 interchangeable holders for the carbon sheets.

Fig. 7 is a perspective view of the carriage on which the holder of Fig. 6 is mounted for movement to and from the platen carriage.

Fig. 8 is a perspective view of a guard plate attached to a carbon-sheet-holding finger.

Referring to the drawings, the platen 7 is fixed on the shaft 8 which is journaled in a frame fast to a rock shaft 9, having bearings in the end plates 10 of the platen carriage. This pivoted frame consists of end plates or arms 11 fast to the rock shaft 9, and connected by a brace bar 12. The platen has its 90 bearings in the plates 11. The frame is normally held in the Fig. 4 position, with the platen down against the usual feed rolls 13 and 14. It is swung from its normal or printing position to its web-releasing position, as shown in United States Letters Patent 1,132,055, to Wernery and Smith, by means of an arm or handle 15 which is also fast to the shaft 9. For locking the platen frame in printing position, the handle 15 100 carries a pin 16 adapted to be engaged by a hook 17 pivotally mounted on a bracket 18 on the end plate 10 of the platen carriage. A spring 19 engages the hook and the bracket to hold the hook in platen-locking 105 position and to return it to such position when free to do so. The nose of the hook is shaped at 20 to permit the pin 16 to cam it backward until the pin can pass under the nose, thereby making the locking operation 110 automatic when the platen frame is swung down to normal position. A tooth 21 on the hook may serve to determine the return throw, and normal position, of the platen 115 in conjunction with a pin or stop 23 on the right-hand end carriage-piece 10 at the front thereof. When the right-hand arm 22 fast on the shaft 9 strikes the pin 23, the platen frame is definitely arrested.

To effect the line-space feed or rotation of the platen, there are provided the usual hand wheel 24 and ratchet wheel 25, both fast to a short shaft 26, mounted to rotate in the left-hand end piece 10 of the carriage. In printing position, the shaft 26 is concentric with the platen shaft 8. The ratchet is actuated by a pawl (not shown) on a slide 27, engaged by a line-space lever 28. The driving connection between the shaft 26, whose axis is not changeable, and the platen 120

shaft 8, which swings from one to another position, consists of gears 29, 30 and 31. The gear 29 is fast to the shaft 26: the gear 30 is fast to the platen shaft, and is of the same size and number of teeth as gear 29: and the gear 31 is loose on the axle 9 around which the platen frame swings, and has a face of sufficient width to simultaneously mesh with gears 29 and 30. The driving connection between the shaft 26 and platen is thus maintained in all positions of the platen.

In Patent No. 1,132,055, to Wernery and Smith, above referred to, it is shown that in the operation of removing a printed length from the web, and in re-adjusting the web for printing the next length, the platen is swung from printing position to a position away from the feed rolls, so that the web no longer wraps around the platen, but may be moved freely in substantially a straight line from back to front of the machine. When the platen is in this position, the carbon sheets between the plies or folds of the section of the web to be removed, are drawn back into the length or section of web next to be printed; and, after removal of a length of the web, and re-positioning of the web, the platen is returned to its normal position against the feed rolls.

The web is preferably in a single piece, fan-folded longitudinally, to provide for several copies when carbon sheets are interleaved with the folds. It may also be in a crosswise fan-folded condition before being fed into the machine to permit of compactness and convenience in handling; or it may be fed from a roll. It is fed into the machine over a bar 33 at the rear of a table 34, having side rails 35 to which the bar 33 is secured. These rails are connected at the front of the table by a bar or tie-rod 36 supported by arms 37 secured to the platen carriage, so that the table has letter-feed movement with the platen. The table frame is further braced by cross-bars 38 and 39, from the intersection of which, depends a bracket carrying a roller 41 which rides on a rail 42 carried by a framework 43, secured to or forming part of the main frame of the machine, and which supports the table 34 at the rear thereof. The web is led across the table and over the top of a paper guide 44 behind the platen (see Fig. 4), whence it is passed down between the platen and the pressure rolls 13 and 14, and thence up between the platen and a pair of paper guides or spring clips 46, one of which is on each side of the printing point. From the guides 46 the web passes between the platen and the web-cutting blade 47, onto the paper shelf 48, to which is secured a gage in the form of a bar 49 having adjustably mounted thereon, the gage-piece 50. The latter is a bent metal strip having openings through which the bar 49 passes,

and an offset portion against which the web can be drawn in measuring the length of the sheet to be cut from the web at the cutter 47. The gage-piece 50 is adjustable along the bar 49 for any desired length of sheet, 71 and is held in adjusted position by a thumb screw 51. The shelf 48 is screwed to the brace 12, which forms part of the swinging platen frame, so that, (as in the machine of the Wernery and Smith Patent 1,132,055, 75 above referred to) the paper shelf may swing with the platen in opening a clear and straight path for the web when a sheet is to be cut therefrom, and when re-adjustment is to be made for the printing of another sheet.

The cutter 47 is shown as a curved blade having a knife edge 52 against which the web can be turned and drawn to cut a section therefrom. Normally it is supported 85 in Fig. 4 position by a pair of arms 53 pivotally mounted on the platen shaft 8. Journaled in the side plate 11 of the platen frame is a rock shaft 54, fast to which are arms 55 having pins 56 which work in cam slots 57 90 in plates 58 integral with the cutter-supporting arms 53. A spring 59 secured at one end to one of the arms 55 and at the other end to the hub of the adjacent cutter arm 53, holds the cutter in normal position with the pins 56 in pockets 57 in the forward ends of the cam slots 57. It will be noted, on reference to Fig. 4, that when the parts are in normal position, there is a space 60 between the guides 46 and the cutter. Such a space would offer an opportunity for the leading edge of the web to be fed outside of the cutter, instead of between the cutter and the platen. To eliminate this possibility, the cutter is adapted to be swung down to Fig. 5 position to catch the web and to guide it in the proper direction. In order that the cutter may have this function as a paper guide, the rock shaft 54, by means of which it is held in normal position, has, fixed thereto, a finger key 61, which may be drawn forward, against the action of the spring 59, from Fig. 4 to Fig. 5 position. This movement of the key 61 forces the pins 56 rearward along the cam grooves 57, thereby rocking the cutter arms downward with the cutter, until the rear ends of the cam grooves determine the Fig. 5 position of the cutter; in which it will be noted that the space between the cutter and the guides 46 has been closed, so that the web must strike the cutter and be guided properly to the shelf 48. It is necessary to have the cutter in the Fig. 5 position only in first adjusting the forward length of the web for printing; and consequently, during this operation, the cutter may be held in this position by sustained pressure on the key 61. As soon as the key is released, the spring 59 returns the cutter to normal Fig. 4 position. 100 105 110 115 120 125 130

The paper guides 46, (see Figs. 1 and 4), are spring metal strips attached to the segment bridge, one on each side of the type guide, and each bearing on the paper at or 5 about the printing line, and near the printing point. These guides serve in the double capacity of paper fingers and line gages; and for the latter purpose, have apertures 64, the lower edges 65 of which serve as base 10 lines for the line of printing on the web and have scale markings 66, to indicate the true letter-positions. By alining the writing with the two base lines thus provided, and by positioning letters in the line at the 15 scale markings, the proper position for any letter to be inserted at the printing point is accurately ascertained.

When the platen frame is thrown up to release the web, and the web is drawn forward to the gage-piece 50 preliminary to cutting, all friction of the several parts on the web has been relieved, with the undesirable consequence that the web in front of the platen may be rocked from true position and 25 may be cut other than squarely, unless care is used in properly alining its leading edge at the gage. To assure this correct positioning of the web at the gage, and to guide the web as it is drawn to the gage, there is 30 mounted, on brace 12 of the swinging frame, a guide in the form of a metal strip 67 which is brought around the upper edge of the shelf 48, and forward a short distance down the outer face of the same, to present 35 a smooth guiding surface for one edge of the web. To secure proper alinement of the web for cutting, it is only necessary, in drawing the paper to the gage-piece 50, to keep its edge in contact with the guide 67. To 40 accommodate the guide 67 to webs of different widths, the guide 67 is adjustable on the platen frame. It is held by a stud 68, which passes from a block 69 on one side of the brace 12 through a slot 70, which extends 45 longitudinally of the brace, and through the supporting portion of the guide 67, to be engaged by a threaded head 71, which may be loosened to permit adjustment of the guide along the slot, and tightened to lock 50 the guide in place. The brace is stamped to provide a channel 72 in which the block 69 may be moved without interference with the overlying shelf 48.

It has been stated that the web is folded 55 longitudinally so that several copies may be made at a time by the use of carbon sheets. These carbon sheets, as above stated, are drawn back from the written portion of the web, into the length thereof next to be written, at the time the web is released and before it is cut. For permitting forward line-space feed of the carbon with the web, and for withdrawing the carbon sheets from the written, to the next unwritten section of the 60 web, there is provided a carriage to which

the rear ends of the carbon sheets are attached. This carriage (see Figs. 1 and 7) consists of a rectangular plate 74, cut away at 75 for lightness, and having at each corner an ear 76 in which is mounted a grooved 70 roller 77. The rollers 77 ride on flanges 78 of the side rails 35 of the paper table, so that the carriage may be moved toward the platen by the line-space feed of the latter, and away from the platen by means of a 75 handle 79. The carbon sheets in the present invention, are not directly attached to the main body of the carriage, but are attached to a plate 80 (see Fig. 6), the center of which is cut out for lightness and which, 80 near each of its corners, has a hole 81, into which a dowel 82 on the bed plate 74 is adapted to enter when the plate 80 is placed upon the bed plate; the plates 74 and 80, being thus locked together. Depending 85 flanges 84 on the plate 80 assist in preventing play or displacement of one plate on the other. Upwardly projecting ears 83 on the bed plate serve as guides for the corner of the plate 80 to assist in registering 90 the dowels 82 with the holes 81 and to enable the plate 80 to be quickly positioned on the bed plate. On the plate 80, at each side of the carriage, is a stepped block 80^a. Fingers or clips 85, to each of which one carbon 95 sheet may be attached, are secured to the steps 86 of the blocks 80^a. These fingers which are somewhat less in length than the width of the web, are staggered; alternate fingers being secured to the same side of the 100 carriage, so that the fingers may lie in the oppositely directed fan-folds of the web. These steps 86 space the several folds of the web so that the fingers which hold the carbon sheets may not bind the same. The 105 web, as soon as it reaches the carriage 74, therefore, becomes interwoven with carbon sheets, the rear edges of which are attached to the fingers 85, and the forward edges of which are free, except that they are clamped 110 between the folds of the web at the platen by the pressure of the feed rolls 13 and 14. Release of this pressure, particularly when the platen is lifted far enough to unwrap 115 the web from it, permits of ready retraction of the carriage, with the carbon sheets, independently of the web.

Heretofore there has been no single holder for all the carbon sheets, which has been readily removable as a unit from the carbon-sheet carriage, and readily mountable as a unit on that carriage. It is because the forms may be frequently changed in a machine of this character, and to avoid the inconvenience on every such change, of separately, and at the time of change, detaching and re-attaching the carbon sheets, that there is provided in the present invention, carbon holders such as the holder 80 which are detachably secured to the carriage 74, 120

and interchangeable thereon. Here, in changing the forms, it is unnecessary to remove the carbon sheets from the same; the plate 80 is removed as a unit with the carbon sheets and the web thereon. The new form, with a plate 80 of its own, and with other carbon sheets already in place, is substituted as a unit for the form which has been temporarily removed. The necessity 10 of maintaining two or more machines for expedition of work on various forms, is therefore obviated.

The holders 80, which are preferably of light material, may, when the platen frame 15 is thrown to web-releasing position, be lifted bodily from the carriage 74 with the web and carbon thereon, by means of the handle 79, which, (see Fig. 6) is riveted to a wing 79^a on the side of the carbon sheet holder 80.

20 At the rear of the paper table is a device 88, which prevents possible backward slipping of the web when the web is released by movement of the platen frame, and is not held by the hand. This device is in the 25 form of a finger pivoted at 89, to a lug 90 on the rear cross-tie 33, and having a bent portion 91, offset over the table, so that when the web is on the table, and the finger 88 is turned down against the web, it exerts 30 sufficient pressure on the latter to prevent backward slipping of the web. It may be held in up or down position by a spring 88^a, which normally bears against the back of the finger, but which, when the finger is 35 turned down against the web, bears against the surface 88^b of the finger.

The equivalent of this device has heretofore been one which has extended from one side of the table to the other, and which 40 would therefore interfere with the removal and placement of webs with the holders 80, as hereinbefore described. The finger 88, however, in nowise offers such interference, as there is space between the end of the finger and the other side of the table through 45 which to pass the webs in changing the forms.

In order to protect the folded web from 50 being torn by the free ends of the carbon-sheet-holding fingers 85, as the holder is returned to a new position relative to the web, guard plates or shields 92, are provided for attachment to the fingers 85. Without such 55 guard plates or shields, the outer corners of the fingers 85 are liable to catch the web, particularly at the folds thereof, especially if the web is skewed sidewise, bent or displaced upwardly from the supporting table, or otherwise moved out of its normal 60 straight course (as indicated in Fig. 3). The danger of the web being thus torn is increased when the web is perforated along its fold, as is common. The shield 92, when placed on a finger 85 projects rearwardly 65 therefrom, and the outer edge of the shield

is inclined inwardly, so that the rearmost end or point 93 of the shield engage the web some distance inward from the fold. The shield thus serves to straighten out or smooth the web, as the carbon-holder is 70 returned, as well as protecting the web from being torn by abruptly engaging the sheet-holding finger.

The guard plate 92 is preferably made of sheet-metal, and is provided with lugs 94, 75 which, when the guard is in position on the finger 85, extend alternately on opposite sides of said finger, the tips 95 of said lugs 94 being offset to engage the front edge of the finger. Said plate is thus readily 80 slipped on or off the said finger, and is frictionally held against displacement. The shield or shields may be applied to the rearmost finger or fingers 85 at one or both ends of the holder, as conditions may require. 85 As indicated in Fig. 3, the shield may be applied outside of the carbon-sheet.

Variations may be resorted to within the scope of the invention, and portions of the improvements may be used without others. 90

Having thus described my invention, I claim:

1. In a typewriting machine, the combination with a platen, of a support for a plurality of webs with interposed transfer material, said webs with their interposed transfer material being presentable at the printing point of the platen, and said webs and transfer material having relative movement to bring the transfer material into register 100 with different successive portions of said webs, and means for holding the transfer material between the webs during said relative movement, said holding means being mounted on said support in a manner to 105 permit the removal of said holding means with the transfer material in place thereon.

2. In a typewriting machine, the combination with a platen, of means for supporting a fan-fold web with a plurality of interleaved sheets of transfer material, said web with its interleaved sheets being presentable at the printing point of the platen, and said web and said sheets of transfer material having relative movement to bring said sheets 115 into register with different portions of the web, means for holding said transfer material between the folds of said web during said relative movement, said holding means being mounted on said support in a manner 120 to permit the removal of the holding means with the transfer material and web in place thereon.

3. In a typewriting machine, the combination with a platen, of a support for a 125 fan-folded web having interleaved sheets of transfer material, said web with its interleaved sheets being presentable at the printing point of the platen, and said web and said sheets having relative movement to 130

- bring said sheets into register with different successive portions of said web, and a device having a plurality of individual retaining means, one retaining means for each sheet of transfer material, said device being mounted on said support in a manner to permit the removal thereof from said support, and said individual retaining means holding said transfer material and said web in place on said device on removal thereof from said support.
4. In a typewriting machine, the combination with a platen, of a support for a fan-folded web with interleaved sheets of transfer material, said web with its interposed transfer material being presentable at the printing point of said platen, and said web and said transfer material having relative movement to bring different sheets of material into register with successive portions of the web, and a plate having a plurality of clips, each clip to intervene between opposite plies of said web and to hold a sheet of transfer material, said plate being mounted on said support in a manner to permit the removal of said plate from said support and said clips holding said transfer material and said web in place thereon during said removal.
5. The combination with a platen, of means for feeding a work-piece in a plurality of plies to the platen; a plate having means for holding transfer material between the plies of the work-piece, a support for the holding plate, and interlocking means for securing the plate against displacement on the support while permitting removal and replacement of the plate with the work-piece and transfer material in place thereon.
6. The combination with a platen, of means for feeding a work-piece in a plurality of plies to the platen, a plate having means for holding transfer material between the plies of the work-piece, a support for the holding plate, interlocking means for securing the plate against displacement on the support while permitting removal and replacement of the plate with the work-piece and transfer material in place thereon, and means for guiding said interlocking means into engagement when the plate is applied to the support.
7. The combination with a platen, of means for feeding a work-piece in a plurality of plies to the platen, means for holding transfer material between the plies of the work-piece, a support for said holder, said holder movable from its support with the work-piece and transfer material in place thereon, and means whereby said support and holder may have a line-space movement with the platen and a reverse movement to re-position the transfer material on the work-piece.

8. The combination with a platen, of means for feeding a work-piece in a plurality of plies to the platen, means for holding transfer material between the plies of the work-piece, a carriage for said holder having movement toward and from the platen, and said holder movable from its carriage with the work-piece and transfer material in place thereon.

9. The combination with a platen, of means for feeding a work-piece in a plurality of plies to the platen, means for holding transfer material between the plies of the work-piece, a support to which said holder is interlocked against lateral displacement, and a handle on the holder for lifting the holder from the support with the work-piece and transfer material in place thereon.

10. The combination with a platen, of means for feeding a work-piece in a plurality of plies to the platen, a plate having means for holding transfer material between the plies of the work-piece, a carriage for the holding plate having movement toward and from the platen, and interlocking means for securing the plate against displacement on the carriage while permitting removal and replacement of the plate with the work-piece and transfer material in place thereon.

11. In a typewriting machine, a rotary platen, means for holding against the platen a web of a plurality of plies with interleaved carbon sheets, means for shifting the platen from said web-holding means to release the web and carbon sheets so that the latter may be drawn backward along the web for the printing of successive sections of the web, means engaging the rear of the carbon sheets for holding the same in position between the plies of the web and for moving the same backward along the web, a carriage for said carbon-sheet holder, and means for detachably securing the carbon-sheet holder to the carriage, so that the holder with the web and interleaved sheets in place thereon may, as a unit, be removed from and attached to the carriage.

12. In a typewriting machine, a rotary platen, means for holding against the platen a web of a plurality of plies with interleaved carbon sheets, means for shifting the platen from said web-holding means to release the web and carbon sheets so that the latter may be drawn backward along the web for the printing of successive sections of the web, means engaging the rear of the carbon sheets for holding the same in position between the plies of the web and for moving the same backward along the web, a carriage for said carbon-sheet holder, means for detachably securing the carbon-sheet holder to the carriage, so that the holder with the web and interleaved sheets in place thereon may, as a unit, be removed

from and attached to the carriage, and means for holding the web against backward slipping when the same is released, said last-named means, when in place, permitting removal and insertion of the web with the holder.

13. In a typewriting machine, a rotary platen, means for holding against the platen a web of a plurality of plies with interleaved carbon sheets, means for shifting the platen from said web-holding means to release the web and carbon sheets so that the latter may be drawn backward along the web for the printing of successive sections of the web, means engaging the rear of the carbon sheets for holding the same in position between the plies of the web and for moving the same backward along the web, a carriage for said carbon-sheet holder, means for detachably securing the carbon-sheet holder to the carriage, so that the holder with the web and interleaved sheets in place thereon may, as a unit, be removed from and attached to the carriage, and a finger partly overlying the web back of the holder, adapted to be moved down against the web to prevent slipping of the latter when it is released by shifting of the platen.

14. In a typewriting machine, a rotary platen, means for holding against the platen a web of a plurality of plies with interleaved carbon sheets, means for shifting the platen from said web-holding means to release the web and carbon sheets so that the latter may be drawn backward along the web for the printing of successive sections of the web, means engaging the rear of the carbon sheets for holding the same in position between the plies of the web and for moving the same backward along the web, a carriage for said carbon-sheet holder, means for detachably securing the carbon-sheet holder to the carriage, so that the holder with the web and interleaved sheets in place thereon may, as a unit, be removed from and attached to the carriage, and a finger partly overlying the web and permanently attached to the machine back of the holder, adapted to be moved down against the web to prevent slipping of the latter when it is released by shifting of the platen.

15. In a typewriting machine, a rotary platen, a platen carriage, means for holding against the platen a web of a plurality of plies with interleaved carbon sheets, means for shifting the platen from said web-holding means to release the web and carbon sheets so that the latter may be drawn backward along the web for the printing of successive sections of the web, means engaging the rear of the carbon sheets for holding the same in position between the plies of the web and for moving the same backward along the web, a carriage for said carbon-sheet holder, means for detachably securing the

carbon-sheet holder to the carriage, so that the holder with the web and interleaved sheets in place thereon may, as a unit, be removed from and attached to its carriage, and a table secured to the platen carriage and having guides on which the carbon-sheet carriage moves.

16. In a typewriting machine, a rotary platen, a platen carriage, means for holding a web to the platen, means for shifting the platen from said web-holding means to release the web, a table over which the web is fed to the platen, said web being removable from and replaceable on the machine, and a finger pivoted to said table and only partly overlying the web so as to be swung down against the web to prevent slipping of the latter when the web is released by the shifting of the platen, said finger being constructed to enable the removal of the web from the machine and the replacement thereon.

17. The combination with a platen, of means for feeding a work-piece in a plurality of plies to the platen, interchangeable means for holding transfer material between the plies of the work-piece, a support for said interchangeable holders, and said interchangeable holders removable from their support with the work-piece and transfer material in place thereon.

18. The combination with means for advancing a web folded lengthwise to form a number of plies, of a holder for a carbon sheet or sheets arranged between the plies, said holder and carbon sheets arranged to advance with the web, and returnable relatively to the web to position the carbon sheet or sheets opposite a fresh portion of the web, said holder comprising a carbon-sheet-holding finger projecting inwardly between plies of the web, and a guard plate or shield carried by said finger to protect the web against being torn by the free end of said finger.

19. The combination with means for advancing a web folded lengthwise to form a number of plies, of a holder for a carbon sheet or sheets arranged between the plies, said holder and carbon sheets arranged to advance with the web and returnable relatively to the web to position the carbon sheet or sheets opposite a fresh portion of the web, said holder comprising a carbon-sheet-holding finger projecting inwardly between plies of the web, and a guard plate or shield carried by said finger to protect the web against being torn by the free end of said finger, said guard being in the form of a plate projecting rearwardly from the sheet-holding finger and having its outer edge inclined inwardly, said plate serving to straighten or flatten the web in advance of the returning carbon sheet.

20. The combination with means for guiding and feeding a web folded fan-shape in

the direction of its length to form a number of plies, a support for carbon sheets interleaved with said plies, said support and carbon sheets arranged to be advanced with the web and be returned relative to the web, to position the carbon sheets opposite a fresh portion of the web, said holder comprising a carbon-sheet-holding finger extending inwardly between two of the plies to a point adjacent the fold uniting said plies, and a plate forming an attachment for said finger, said plate projecting rearwardly from said finger to move in advance of said finger as the carbon-sheet-holder is returned and thereby flatten or straighten the web if it has become displaced.

21. The combination with means for guiding and feeding a web folded fan-shape in the direction of its length to form a number of plies, a support for carbon sheets interleaved with said plies, said support and car-

bon sheets arranged to be advanced with the web and be returned relative to the web, to position the carbon sheets opposite a fresh portion of the web, said holder comprising 25 a carbon-sheet-holding finger extending inwardly between two of the plies to a point adjacent the fold uniting said plies, and a plate forming an attachment for said finger, said plate projecting rearwardly from said 30 finger to move in advance of said finger as the carbon-sheet-holder is returned and thereby flatten or straighten the web if it has become displaced, said plate having forwardly extending lugs to engage alternately 35 on opposite sides of said finger, for holding the plate in position and permitting it to be removed from said finger.
